FOREIGN PATENT DOCUMENTS

JP 5-18490 1/1993

Primary Examiner — John Windmuller*Assistant Examiner* — Steven Czyz(74) *Attorney, Agent, or Firm* — Faegre Baker Daniels LLP(57) **CLAIM**

The ornamental design for an expandable sealing mechanism, as shown and described.

DESCRIPTION

FIG. 1 is a perspective view of an expandable sealing mechanism;

FIG. 2 is a front elevation view thereof;

FIG. 3 is a top plan view thereof;

FIG. 4 is a bottom plan view thereof;

FIG. 5 is a side elevation view thereof, it being understood that left and right sides views of the expandable sealing mechanism are identical;

FIG. 6 is a bottom perspective, exploded view thereof; and, FIG. 7 is a side elevation, cross-sectional view taken along line 7-7 as shown in of FIG. 5.

The broken lines depict portions of the article that form no part of the claimed design.

1 Claim, 5 Drawing Sheets(56)
